George A. Gast, Chicago, Ill., assignor to
Raymond T. Moloney, Chicago, Ill.

Application July 19, 1952, Serial No. 20,691

Term of patent 14 years

(Cl. D26—13)

To all whom it may concern:

Be it known that I, George A. Gast, a citizen of the United States of America and a resident of Chicago, Cook County, Illinois, have invented a new, original, and ornamental Design for a Remote Control Unit for Television Receivers and the like, of which the following is a specification, reference being had to the accompanying drawing, forming a part hereof.

Fig. 1 is a top plan view of a remote control unit for television receivers and the like showing my new design;

Fig. 2 is a bottom plan view of the same;

Fig. 3 is a side elevation of the same;

Fig. 4 is an end view of the same;

Fig. 5 is an opposite end view of the same.

I claim:

The ornamental design for a remote control unit for television receivers and the like, as shown.

GEORGE A. GAST.
